JOHN A. LIGHTHALL AND REUBEN LIGHTHALL, OF BROOKLYN, NEW YORK.

Letters Patent No. 77,388, dated April 28, 1868.

IMPROVEMENT IN THE MANUFACTURE OF GLUE.

The Schedule referred to in these Letters Patent and making part of the same.

TO ALL WHOM IT MAY CONCERN:

Be it known that we, JOHN A. LIGHTHALL and REUBEN LIGHTHALL, both of the city of Brooklyn, in the county of Kings, and State of New York, have invented certain new and useful Improvements in the Manufacture of Glue; and we do hereby declare that the following is a full and exact description of the same, reference being had to the accompanying drawings, and to the letters of reference marked thereon; in which—

Figure 1 is an elevation of the apparatus, a portion of the left-hand side being broken away to show more perfectly the arrangement.

Figure 2 is an end view of the same, and

Figure 3 a detached sectional view of one of the series of plates used.

In the ordinary process of making glue, the glue-stock, after being properly prepared, is cooled in vessels, and when it has attained a solid state, is cut into slices or cakes of the ordinary thickness of commerce, and laid upon nets to be dried.

The disadvantages of this process are mainly in the drying-process. As the product is exposed to the atmosphere to produce the drying, it is subject to all the atmospheric changes, by which it is sometimes frozen by extreme cold, and again made liquid by extreme heat. And again, that in consequence of damp and foggy weather, the stock remains so long on the nets as to be rotted and rendered worthless, as is the case with the former conditions named, the stock in either case being worthless, and having no marketable value.

To remedy and overcome the difficulties and disadvantages above named is the object and purpose of our invention, which consists of an apparatus, as hereinafter described, by which glue can be made at all times and all seasons, irrespectivo of the weather, and of the condition and state of the external atmosphere; and further, in making such glue of a uniform thickness, of such thickness as to be readily dissolved for use, the glue as made by the ordinary process being of such thickness as to require a considerable length of time to dissolve it ready for use, whereas the glue made by our process is of so much less thickness that it is readily and quickly dissolved. Besides, the glue, as made by our process, is of a uniform thickness, which has not been before attained by any other process in the manufacture of glue of less thickness than the ordinary glue of commerce, allowing thereby the whole of the glue to be dissolved and prepared for use at one and the same time, which in practice is found to be a great advantage.

In the drawings hereunto attached, A A' are two flues, of proper shape and height, which may be made of wood, metal, or brick-work, the size in transverse section being made suitable to the amount of glue required to be cooled and made, and the height so proportioned as to effect the objects hereinafter named. The two flues are secured by any required means to or upon the reservoir B, which contains the prepared material from which the glue is to be made, and are connected at their top ends with the escape or stack C, through which the air escapes, as hereinafter described.

B is the reservoir, into which the prepared material for making the glue is placed, the process up to the point of putting the product in the reservoir being the same as ordinarily practised.

D D' are two pulleys or drums, revolved either by hand or by power applied to the pulley E, around which is placed the endless belt F. This belt may either be made of leather, the same as an ordinary belt for driving machinery, or, as can readily be seen, be made of an endless chain, to effect the same purpose.

To the exterior of this belt is secured (in any desired way) the series of plates G to G⁶, these plates being made of thin metal, sheet iron, sheet zinc, sheet tin, or sheet brass, of such number to each set as to nearly fill up the space of the width of the flues. The object and purpose of making these plates of thin metal will be further explained below.

On the ascending side of the flue, as marked by the arrow, a blowing-apparatus of any desired form is placed, which blows its blast of cold air first into the receiver H, and is from thence taken away into the flue at or about the point shown. The quantity of air to be so blown into the flue is regulated by the throttle-valve I, and the receiver is provided with a lightly-loaded safety-valve, J, so that in case of a surplus quantity being driven into the receiver over what is required to be taken into the flue, the same may escape through and by the said valve.

The object, intent, and purpose of this cold blast of air upon the plates passing upward through the flue is, primarily, to fasten the glue that is taken up by the plates in their passage through the material in the reservoir B, so as to prevent the dripping of the material from the same, in order that the product left upon the plates shall be of an even and uniform thickness; and, secondly, to dissipate and carry off, by the way of the stack C, a considerable amount of the water contained in the material.

On the descending side of the flue are located and placed a similar blowing-apparatus and receiver, differing in nothing from the former one, except that the blast from this blower is heated to such point as to subserve two distinct purposes, one being the removal of all the balance of contained moisture in the material that is not removed and taken away by the cold blast, and the other being the removal, from the thin plates, of the perfectly dried glue, which drops off from the plates and is delivered through the spout L. The heated air from this blower ascends and is taken off by the stack C, the combination of the cold and hot blasts with the vapor taken off from the material naturally creating a very powerful draught, which renders the use of a stack of great height unnecessary.

We find in practice the glue thoroughly dried on thin plates, as above stated, will readily remove and drop off from the plates when the proper degree of drying-heat is applied, but it can readily be seen that in case of a slight variation of heat not producing that effect, the dried glue can be removed by mechanical means.

We do not confine ourselves to the use of the receivers before named, as they may possibly be dispensed with, and the proper supply of air regulated by other means that will subserve the same purpose.

What we claim as our invention, and desire to secure by Letters Patent, is—

1. The combination of the series of plates with the belt and driving-pulleys, as and for the purpose set forth.
2. In combination with the series of plates, attached to the belt, as before named, the arrangement for blowing a blast of cold air on the said plates after they have been dipped into the reservoir, for the purpose of preventing the drip from the same, so that the glue attached to the plates shall be preserved of an equal and uniform thickness.
3. In combination with the series of plates, attached to the belt, as before named, the arrangement for blowing a blast of hot air on the said plates on the descending side of the apparatus, for the double purpose of removing from the glue attached to said plates any moisture that may remain in it, and for removing the finished glue from the plates, as set forth.

JOHN A. LIGHTHALL,
REUBEN LIGHTHALL.
